SHINGLE

Henry B. Hutton, Joliet, Ill., assignor to The
Ruberoid Co., New York, N. Y., a corporation of
New Jersey

Application March 4, 1936, Serial No. 67,613

2 Claims. (Cl. 168—7)

This invention relates to shingles for roofing and siding purposes, and more particularly to individual shingles of the type that form hexagonal patterns when laid.

5 Among the objects of my invention are to provide shingles of that type which are self-aligning; which may be accurately and rapidly laid without recourse to guide lines or other guiding marks; which are economical of material in forming a water-tight covering; and, which 10 form a covering of pleasing and attractive appearance.

Further objects and advantages of the invention will appear from the following description 15 thereof, reference being had to the accompanying drawing, in which:

Figure 1 is a plan view of a shingle embodying my invention; and

Fig. 2 is a plan view of an assemblage of the 20 shingles laid in overlapping rows to form a covering.

The shingle 10 is of substantially hexagonal form having parallel upper and lower horizontal edges 11 and 12, and inclined side edges 13, 14, 25 15 and 16. The upper and lower edges are preferably shorter than the side edges.

At one side corner of the shingle, between the inclined edges 13 and 14, there is a rectangular projection or tab 17 having a lower horizontal edge 18, an upper horizontal edge 19, and a vertical edge 20. The edges 18 and 19 are of equal 30 lengths but are shorter than the vertical length of the edge 20. The opposite side corner of the shingle, between the inclined edges 15 and 16, has a triangular projection or tab 21 having a horizontal edge 22 and a vertical edge 23 of substantially equal lengths. The horizontal edges 18 and 22 of the two tabs are each preferably one-half as long as the length of the upper 35 or of the lower edge of the shingle.

The shingles are laid horizontally in rows with the vertical edge 20 of the tab 17 of one shingle abutting the vertical edge 23 of the tab 21 of the adjacent shingle of the same row, and with the horizontal edges 18 and 22 of the two tabs in alignment. They are then nailed or secured in place in the usual manner. The shingles of each 40 succeeding row are placed so that the lower

edges 12 of the overlying shingles register with the horizontal edges 22—18 of the tabs of two contiguous shingles of the immediately underlying row, and with the upper edges 19 of the tabs 17 of the overlying shingles in alignment with the upper edges 11 of the shingles of the underlying row.

An important feature of my improved shingle is that it provides for visual alignment or registration with the underlying shingles at two 10 separate and distinct places. This makes it possible to lay the shingles more rapidly and with greater accuracy than any of the prior art shingles of this type.

My improved shingles, when laid as shown in 15 Fig. 2, have a relatively large ratio of exposed to unexposed area and hence are economical of material in forming a water-tight covering. The shingles, furthermore, are self-aligning both as to adjacent shingles of the same row and as to 20 shingles of the underlying row.

What I claim is:—

1. A self-aligning shingle of substantially hexagonal form having horizontal upper and lower edges, inclined side edges meeting the upper and lower edges, a triangular projection at one side corner, and a rectangular projection at the opposite side corner, said rectangular projection having a horizontal upper edge which is adapted to align with the upper edge of an underlying 30 shingle.

2. A roof covering laid with shingles of substantially hexagonal form having horizontal upper and lower edges, inclined side edges meeting the upper and lower edges, a triangular tab at one 35 side corner, a rectangular tab at the opposite side corner, said triangular tab having a horizontal lower edge and said rectangular tab having horizontal upper and lower edges, the tabs of adjacent shingles of each course abutting each other with their lower horizontal edges in alignment, each overlying shingle being laid with its lower edge in alignment with the lower edge of the abutting tabs of two underlying shingles and with the upper edge of its rectangular tab in 45 alignment with the upper edge of an underlying shingle.

HENRY B. HUTTON.
